United States Patent Office

Des. 189,129
Patented Nov. 1, 1960

189,129

COMBINED OUTDOOR TELEPHONE ENCLOSURE AND SUPPORT

Henry G. Turner, Atlanta, Ga., assignor to American
Telephone and Telegraph Company, New York, N.Y.,
a corporation of New York

Filed Sept. 15, 1959, Ser. No. 57,562

Term of patent 14 years

(Cl. D13—1)

FIG. 1

FIG. 2

FIG. 3

FIG. 4

Fig. 1 is a front perspective view of a combined outdoor telephone enclosure and support showing my new design with the phone shown in broken lines for illustrative purposes only;

Fig. 2 is a side elevation;

Fig. 3 is a front elevation; and

Fig. 4 is a top plan view on a reduced scale.

The dominant features of my design reside in the portions shown in full lines.

I claim:

The ornamental design for a combined outdoor telephone enclosure and support, as shown and described.
